(57) **CLAIM**

The ornamental design for a fuel tank with cap for drone, as shown and described.

DESCRIPTION

FIG. 1 is a front perspective view of fuel tank with cap for drone embodying my new design;

FIG. 2 is a front view elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is a rear perspective view thereof showing the cap exploded from the fuel tank; and,

FIG. 10 is a rear perspective view thereof showing the cap exploded from the fuel tank and in a state of use.

1 Claim, 10 Drawing Sheets
